UNITED STATES PATENT OFFICE.

WILLIAM J. OVERBECK, OF CINCINNATI, OHIO.

TREATMENT OF CANDIES AND THE LIKE AND THE PRODUCT OBTAINED THEREBY.

1,327,113.

Specification of Letters Patent.

Patented Jan. 6, 1920.

No Drawing.

Application filed October 7, 1918. Serial No. 257,209.

To all whom it may concern:

Be it known that I, WILLIAM J. OVERBECK, a citizen of the United States, and a resident of Cincinnati, in the county of Hamilton and State of Ohio, have invented certain new and useful Improvements in the Treatment of Candies and the like and the Product Obtained Thereby, of which the following is a specification.

10 Heretofore in order to properly preserve candies which are liable to be softened and injured by moisture, or in which the flavors are readily dissipated, it has been customary to apply to the finished goods a fine coating of shellac.

It has become quite common to treat various vegetable oils with hydrogen in the presence of a catalyst to convert the components of the oil into a fully saturated condition so that the resulting product is solid at atmospheric temperatures.

I have discovered that if such hydrogenated oil is deposited in finely divided particles over and through the candies when finished, a filmy deposit of the hydrogenated oil is formed on the candies, which thoroughly protects the candies from absorbing moisture or deterioration, and that such film is capable of forming a fine glaze or finish, which adds much to the attractiveness and salability of the goods. By agitation of the candy in a drum or receptacle, the film is susceptible of taking on a high degree of polish and the deposit is not otherwise perceptible, while by the selection of an edible oil the treatment is in no way objectionable or injurious, which can hardly be claimed for the use of the shellac varnish.

In the production of my new product, my aim is to thoroughly coat the candy with a thin film of the hardened oil, and this may be accomplished by subjecting the candies to agitation in the presence of lumps of the hardened oil, or by a deposit thereon of the hydrogenated oil in solid or powdered condition, or in any other ways that may readily suggest themselves.

I have found one method which produces most satisfactory results. In this method, which is given as an illustration and not with any intention of limiting the invention to the product of any particular process, I

make use of an air gun or atomizer for discharging a mist or spray of the hardened oil in finely divided condition over and through the candies. In carrying out this method, I heat the oil and reduce it to a liquid form, and then in the ordinary way of atomizing a liquid and with any suitable apparatus for that purpose, I blow a spray or mist of the oil in and over the candies. The oil is divided into very fine particles by the atomizer, and whether the particles are in liquid, semi-liquid or solid condition when the candy is treated with the spray, I find that with this treatment the fine particles which deposited on the goods and then by the rubbing together of the candies, the particles are distributed by attrition so as to form a thin film of solid hydrogenated oil which thoroughly protects the candy from the escape of moisture or the flavors from within, or the admission of moisture, air or other deleterious substances or the production of undesirable effects from without.

As indicated in the preceding paragraph, the desired quantities of solid hydrogenated oil can be transferred to the surface of the candies by bringing the candies in rubbing contact with the hard oil in revolving or agitated containers, the forward walls of which have been previously lined with the solid hydrogenated oil. The candies to be coated, together with suitable sized lumps of the oil, may be introduced into container and by agitation or rotation the candies may be brought into continuous rubbing contact with the lumps as with the lined walls described, and thus by attrition receive the film. This agitation in a drum or container also gives a high degree of polish and a fine glaze or polish to the goods.

Having thus described my invention, what I claim as new and desire to secure by Letters Patent, is:—

1. As a new product, candies coated with hydrogenated oil, in the form of a thin, continuous, even layer of high polish.
2. As a new product, candies with hydrogenated oil, evenly coated thereon by the agitation of the candies in the presence of solid hydrogenated oil.

WILLIAM J. OVERBECK.
